US0D1071166S

(12) **United States Design Patent** (10) **Patent No.:** **US D1,071,166 S**
(45) **Date of Patent:** **** Apr. 15, 2025**

(54) **MEDICAL SYRINGE**

(71) Applicant: **STEVANATO GROUP S.p.A.**,
Piombino Dese (IT)

(72) Inventors: **Karl Hewson**, Cambridge (GB); **Ben Kubler**, Cambridge (GB); **Adam Jonathan Frederick Stops**, Piombino Dese (IT)

(**) Term: **15 Years**

(21) Appl. No.: **35/519,673**

(22) Filed: **Oct. 12, 2023**

(80) **Hague Agreement Data**

Int. Filing Date: **Oct. 12, 2023**

Int. Reg. No.: **DM/234275**

Int. Reg. Date: **Oct. 12, 2023**

Int. Reg. Pub. Date: **Jan. 12, 2024**

(51) **LOC (15) Cl.** **24-02**

(52) **U.S. Cl.**

USPC **D24/113**

(58) **Field of Classification Search**

USPC D24/108, 112–114, 133, 186, 129–130
CPC A61M 5/1452; A61M 5/3156; A61M 5/31591; A61M 5/3155; A61M 5/3157; A61M 5/31501; A61M 5/14566

See application file for complete search history.
